UNITED STATES PATENT OFFICE.

RALPH A. GILBERT, OF PITTSFIELD, MASSACHUSETTS.

INDUCTION COIL.

Application filed February 26, 1925. Serial No. 11,716.

This invention relates to induction coils and aims to provide a novel and improved device of this class. The invention is particularly but not exclusively adapted for 5 use in ignition systems for explosive engines and will best be understood by a description of one selected embodiment thereof, reference being had to the accompanying drawings illustrating the same, wherein,—

10 Fig. 1 is a vertical longitudinal section of the induction coil;

Fig. 2, a cross-sectional view on the line 2—2 of Fig. 1, showing the end-caps of the windings and field-plates assembled thereon; 15 and

Fig. 3, a cross-sectional view of the end-cap on the line 3—3 of Fig. 2.

Referring to the drawings illustrating one selected embodiment of my invention, the 20 housing 10 contains the usual primary and secondary windings 11, 12 grouped about a magnetic core 13 and provided with suitable leads for connection with the induction circuit and the ignition circuit, respectively. 25 The core is of the usual type employed in an open magnetic circuit, comprising a bundle of soft iron wires.

The housing herein illustrated is cylindrical in form and constructed of suitable 30 non-conductive material, the upper end being closed by a removable insulation cover 14 in which are imbedded at opposite points in its side wall a pair of exposed terminals 15 for connection with opposite ends 16 of the primary or low-tension winding 11, and the bottom being closed by a metallic plate 17 fitted into the interior of the housing. This bottom plate is peripherally provided 35 with a depending annular flange 18 adapted to fit into the housing 10, the lower extremity of the flange being bent outward to form a suitable seat 19 for the support of the housing. It will be observed that this seat operates as a stop to limit the extent to 45 which the winding assembly may be inserted into the housing.

The secondary or high tension winding 12 is connected at one end 43 to a terminal 20 mounted on the outer face of the housing, 50 the opposite end 37 of the winding being connected to ground by any convenient means, as, for example, by contact with the bottom plate 17.

The windings and core form a unitary assembly fitted at opposite ends into end-caps 55 21 which suitably insulate and protect the

windings, the ends of the core being each seated in a corresponding circular recess 22 provided centrally on the inner face of the end-caps. A bore 23 communicating with the recess 22 is provided centrally in each of the end-caps to receive one end of a tie-rod 24 which extends lengthwise centrally through and beyond each end of the core and holds the associated parts of the winding assembly, including the end-caps, in rigid relationship. The tie-rod constitutes a rigid supporting element on which the winding assembly is detachably secured to and within the housing, and for this purpose is preferably threaded at each of its extremities beyond the core and carries on its upper end a washer 25 and nut 27 to secure the upper end-cap against displacement, while the lower end carries a washer 26 and is preferably screwed into a threaded recess provided on the inner face of a metallic stud 28 secured to the bottom plate 17 and projected through a central opening therein into the interior of the housing 10. Said stud is formed at its lower end with a reduced threaded extension 29 adapted to receive a nut or other suitable locking member (not shown) for engagement with a support. The tie-rod 24 is extended at its 85 upper end beyond the nut 27 for projection into an interiorly threaded socket member 30 transversely imbedded centrally in the housing cover 14, which is thereby firmly held in detachable position on the housing. Said socket member is provided with a central opening in its bottom to receive the upper extremity of the tie-rod which engages with a threaded locking member 31 seated in the lower end of the socket member. I 90 also preferably provide a removable screw 32 in the exposed upper end of the socket member on the surface of the cover 14 for detachable connection with an independent support when necessary.

Mounted on the exposed ends of the core 13 and engaging the outer face of each of the end-caps 21, I provide field-plates 33 each consisting preferably of two or more soft iron laminæ held firmly in their respective positions by the nut 27 and stud 28 and the intervening corresponding washers. Each of these laminæ contains a radial slot 34, all the slots being arranged in registering position, and also with oppositely arranged transverse openings 35 adapted to receive with respect to the upper field-plate

the upper ends of the leads 16, which are suitably protected by an insulation covering 36, and with respect to the lower field-plate, one of such openings is utilized to receive 5 the lead 37 of the secondary winding. The end-caps 21 are also provided with suitable oppositely arranged transverse openings 38 adapted to register with the openings 35 in the field plates and to receive corresponding 10 leads of the windings.

The radial slots 34 of the end-plates are employed to break up the eddy currents induced therein by the field flux and which have the effect of opposing the magnetic 15 field or flux of the core, thereby destroying the efficiency of the induction coil. It is essential, therefore, that these slots should all be arranged in registering position where a plurality of laminæ are employed, to avoid 20 the effect of eddy currents otherwise set up. It frequently occurs in the manufacture of devices of this class that unskilled labor is employed to assemble the parts of the coil and the work is done in such haste that the 25 slots of the field-plates are not arranged in proper registering position. After completion and test, it is always costly and sometimes difficult to ascertain just wherein the defect lies. To avoid these errors I provide 30 on the outer face of each of the end-caps 21 an extension member 39 forming a key adapted to register with said slots 34 of the end-plates and to maintain them in the registering position. Said member 39 is preferably 35 of such proportions that it will fit readily into said slots and extensively engage the margins thereof to prevent both a turning movement and side play of the field-plates. I also preferably provide on each 40 of the end-plates an additional extension member of reduced dimensions forming a boss 40 disposed opposite the extension member 39. Said boss extends into a suitable transverse opening 41 provided in the field- 45 plates and cooperates with the extension member 39 to facilitate correct assembly and to prevent rotative movement of the plates.

To further consolidate the lines of the field flux at their weakest point, intermediate 50 the ends of the core and the corresponding field-plates, I provide an open band 42 of magnetic metal surrounding the windings and intermediate the end-caps. Said band has a tendency to attract and consolidate 55 the diverging lines of force passing between opposite ends of the core and is preferably constructed with a gap or opening therein forming disconnected free ends, after the manner of the plates 33, for the purpose of 60 preventing the formation of eddy currents. This band I preferably permanently secure to the inner wall of the housing 10 so as not to interfere with the introduction or removal of the winding assembly, the inner end of 65 the terminal 20 being extended through a

suitable opening in the band and thereafter spun or burred over to form a holding shoulder.

It is manifest that my device is operable in any position and may be mounted in any 70 location found convenient for the purpose and affording a suitably conductive surface for ground connection.

It will be understood that the present invention is not intended to be restricted to the 75 particular embodiment herein shown and that obvious modifications may be made therein without departing from the principle of the invention.

I claim as my invention:

1. In an induction-coil, in combination, a core, primary and secondary windings surrounding the core, caps enclosing the windings, and laminated field plates arranged on at least one of the caps, said field plates each 85 having a radial slot therein, and means provided on the corresponding cap for requiring all of the field plates to be assembled with the slots in registering position.

2. In an induction-coil, in combination, a 90 core, primary and secondary windings surrounding the core, caps enclosing the windings, and field plates arranged on the caps, said field plates each having a radial slot 95 therein, and a registering member provided on the caps and adapted to extend into said slots.

3. In an induction-coil, in combination, a core, primary and secondary windings grouped about the core, caps enclosing the 10 windings, and field plates arranged on the caps, said field plates each having a radial slot therein and an opening through the plate opposite such slot, and registering members on the caps for extending into said 10 slot and said opening respectively.

4. In an induction-coil, in combination, a core, primary and secondary windings surrounding the core, caps enclosing the ends of the windings, and field plates arranged on 11 the caps each having a radial slot therein, and an extension member provided on the caps adapted to fit into said slots for arranging and maintaining the field plates in the operative position.

5. In an induction-coil, in combination, a core, primary and secondary windings grouped about the core, caps enclosing the windings, field plates arranged on the caps each having a radial slot therein, a tie-rod 12 for securing the foregoing parts in fixed relationship, and means provided on the caps and cooperating with the field plates for insuring the assembling of the field plates with said slots all in registering position with respect to one another.

In testimony whereof, I have signed my name to this specification.

RALPH A. GILBERT,
